KEY PULSING SENDER FOR TELEPHONE SYSTEMS

Maurice S. Snell and Esmond P. G. Wright,
London, England, assignors to Western Electric
Company, Incorporated, New York, N. Y., a cor-
poration of New York

Application January 20, 1938, Serial No. 185,858
In Great Britain February 12, 1937

8 Claims. (Cl. 177—380)

This invention relates to automatic telephone exchange systems and more particularly to a key pulsing sender for enabling an operator to control the setting of selector switches for establishing connections to desired subscribers' lines.

It has been found that connections requiring the assistance or services of an operator in their establishment can be more expeditiously handled if the operator's dial is replaced by a keyset since the operator is enabled to operate the keyset keys at a much faster rate than she could operate a dial. This operating procedure is particularly advantageous in private branch exchange systems since less time is consumed by operators in establishing desired connections and thus fewer operators are required and they have more spare time to attend to other duties which may be assigned to them.

Keyset controlled senders, commonly known as key pulsing senders, have heretofore been provided in which the digits keyed on a keyset have been registered by groups of register relays or register switches which are then rendered instrumental in controlling the setting of selector switches. It has also been proposed to utilize groups of condensers selectively chargeable for registering the digits of wanted line numbers and to control the setting of selector switches in accordance with the registration indicated by the groups of condensers. The present invention relates to a key pulsing sender of the latter type in which groups of condensers are employed as digit registers and has for its object the provision of a sender circuit which is simpler in construction, less expensive to manufacture and to maintain and more reliable in operation.

In accordance with the embodiment of the invention selected as illustrative, these objects are attained by the provision of as many groups of condensers serving as registers as are required to register the maximum number of digits of a subscriber's number. To simplify the disclosure it has been assumed that the sender is allocated to the use of an operator in a private branch exchange system from which connections may be extended to subscribers' lines having three-digit directory numbers. It will, of course, be obvious that the proposed system could be readily extended for use in larger exchange areas in which subscribers' lines would have directory numbers of more than three digits and could be used, for example, at "A" operators' or toll operators' switchboard positions. Each group of condensers comprises five condensers, any one of which may be charged either positively or negatively to reg-

ister digits 1 to 0, inclusive, keyed by the operator on a ten-button keyset, the condensers being charged negatively to register digits 1 to 5, inclusive, or positively to register digits 6 to 0, inclusive.

Two condenser timed relays are provided for generating impulses which are transmitted for setting selector switches and for operating a train of three counting relays, each digit series 10 of impulses transmitted being terminated by a polarized stop relay under the control of the counting relays and the condenser registers. For 15 successively associating the groups of condensers with the keyset during the keying of the digits of a line number and for thereafter successively associating the groups of condensers successively with the counting and stop relays to control the transmission of series of impulses for setting selector switches in accordance with the digits registered by the groups of condensers, a single set of sequence relays is provided.

While the sender has been disclosed as applicable to the control of selector switches controlled by directive impulses, it is to be understood that its applicability is not so limited, but that by obvious modifications it could be applied to telephone systems employing other well-known types of switching apparatus.

For a more complete understanding of the invention reference may be had to the following detailed description taken in connection with the accompanying drawings in which:

Fig. 1 shows a ten-button keyset for the use of an operator in registering the digits of line numbers and such other control equipment of an operator's position as is deemed necessary to a comprehension of the invention; and

Fig. 2 shows the equipment of a register sender.

For a more complete disclosure of the invention, Fig. 2 should be placed beneath Fig. 1 with the lines extending toward the upper margin thereof in alignment with the corresponding lines extending toward the lower margin of Fig. 1. For a more complete disclosure of the operator's position equipment shown schematically in Fig. 1, reference may be had to British Patent No. 476,048, granted to E. P. G. Wright and G. C. Hartley.

It will be assumed that in response to the illumination of a signal lamp, not shown, indicating that the services of the operator are required for completing a desired connection to a line whose directory number is 275 and which number has been communicated to the operator by the calling subscriber in the manner disclosed

in the patent herein referred to, the operator depresses the start key SK thereby causing the operation of relay S. The operation of relay S prepares a locking circuit for itself over its No. 3 contact and conductor SLL, connects ground over its No. 2 contact, the No. 4 back contact of relay NU, the No. 3 back contact of relay PC to conductor GD for supplying a holding ground for the relays of the sender of Fig. 2 and over its No. 6 front contact supplies operating and holding ground for relays of the position equipment of Fig. 1.

The operator now proceeds to depress keys of the keyset KS to record the number of the desired subscriber's line communicated to her by the calling subscriber. Under the assumption that the number of the desired subscriber's line is 275, she will first depress the No. 2 key of the keyset whereupon an operating circuit is established for relay PP extending from ground over the right contacts of the operated key, conductor 11 to battery through the winding of relay PP. Relay PP operates, opens the normally closed charging circuit of condenser C1 extending over the No. 1 and No. 2 back contacts of relay PP, opens at its No. 3 back contact a discharge circuit for condenser C2, at its No. 3 front contact closes a charging circuit for condenser C2 extending from ground, through this condenser and resistance R1 to battery and at its No. 4 contact establishes a circuit from battery, through resistance R2, conductor 12, the left contacts of the operated key, conductor 13, the No. 3 back contact of transfer relay XX to ground through condenser Cb1 of the first group of register condensers RG1. Condenser Cb1 now becomes negatively charged to register the keyed digit 2.

When the operator thereafter releases the depressed key, relay PP releases, opening the charging circuit just traced through condenser Cb1, reclosing the charging circuit for condenser C1, opening the charging circuit of condenser C2 and establishing a discharge circuit for condenser C2 extending from ground, through this condenser, over the No. 3 back contact of relay PP, the No. 8 back contact of relay CA, the No. 3 back contact and upper winding of sequence relay X to ground. The discharge of condenser C2 over this circuit operates sequence relay X which thereupon locks in a circuit from battery through its lower winding and No. 4 contact, No. 3 back contact of sequence relay Z to ground on conductor GD and at its No. 2 contact establishes an obvious operating circuit for transfer relay XX. Relay XX now operates, disconnecting at its back contacts the condensers of the first register RG1 from the group of conductors 15 extending to the keyset and connecting the condensers of the second register RG2 over the back contacts of transfer relay YY and front contacts of transfer relay XX to the group of conductors.

The operator next depresses the No. 7 key of the keyset whereupon an operating circuit for relay PP is established extending from ground on conductor NU, the right contacts of the operated key, conductor 11 to battery through the winding of relay PP. Relay PP operates again closing the charging circuit for condenser C2 and closing a discharging circuit for charged condenser C1 which may be traced from ground, through resistance R3, the No. 1 front contact of relay PP, condenser C1, the No. 2 front contact of relay PP, conductor 14, the left contacts of the operated key, conductor 13, the No. 3 front con-

tact of transfer relay XX, the No. 3 back contact of transfer relay YY, through condenser Cb2 of the second register RG2 to ground. Condenser C1, which is of higher capacity than register 5 condenser Cb2, therefore discharges into condenser Cb2, charging it positively to register the second keyed digit 7.

When the operator thereafter releases the depressed key, relay PP releases, opening the 10 charging circuit just traced through condenser Cb2, closing the charging circuit of condenser C1 which may now be traced from ground over the No. 2 back contact of relay PP, condenser C1, the No. 1 back contact of relay PP, through resistance R4 to battery, opening the charging circuit of condenser C2 and closing a discharge circuit for this latter condenser extending from ground, through condenser C2, over the No. 3 back contact of relay PP, the No. 8 back contact of relay CA, the No. 3 front contact of sequence relay X, thence over the No. 4 back contact and upper winding of sequence relay Y to ground. The discharge of condenser C2 over this circuit operates sequence relay Y which thereupon locks in a 15 circuit from battery through its lower winding and No. 3 contact, the No. 3 back contact of sequence relay Z to ground on conductor GD and at its No. 2 contact establishes an obvious operating circuit for transfer relay YY. Relay YY now operates, disconnecting at its back contacts 20 the condensers of the second register RG2 from the group of conductors 15 extending to the keyset and connecting the condensers of the third register RG3 over its own front contacts and the front contacts of transfer relay XX to the group 25 of conductors.

The operator next depresses the No. 5 key of the keyset whereupon an operating circuit for relay PP is established which may be traced from 30 ground over the right contacts of this key, conductor 11, through the winding of relay PP to battery. Relay PP operates again closing the charging circuit for condenser C2, prepares a discharge circuit for condenser C1 which, however, is not effective at this time, and at its No. 4 contact establishes a circuit from battery through resistance R2, conductor 12, the left contacts of the operated key, conductor 16, the No. 6 front contact of transfer relay XX, the No. 6 front contact of transfer relay YY, through condenser Ce3 of the third register RG3 to ground. Condenser Ce3 now becomes negatively charged to 35 register the third keyed digit 5.

When the operator thereafter releases the depressed key, relay PP releases, opening the 40 charging circuit of condenser Ce3 just traced, closing the charging circuit of condenser C1, opening the charging circuit of condenser C2 and closing a discharge circuit for this latter condenser which may be traced from ground, through condenser C2, over the No. 3 back contact of relay PP, No. 8 back contact of relay CA, the No. 3 front contact of sequence relay X, the No. 4 front contact of sequence relay Y to ground 45 through the upper winding of sequence relay Z. The discharge of condenser C2 over this circuit operates sequence relay Z which thereupon locks from battery, through its lower winding and No. 4 contact to ground on conductor GD, opens at its No. 3 back contact the locking circuits of sequence relays X and Y which now release, closes at its No. 5 contact an obvious operating circuit for relay ZZ and over its No. 1 contact establishes a circuit for starting the operation of the 50 impulse generating relays A and AA.

Relay ZZ upon operating connects ground to conductor STL to hold relay S of the operator's position circuit operated and over its lower contact extends ground on conductor GD to the locking contacts of sequence relays X and Y preparatory to locking these relays upon their subsequent operation.

When sequence relay Z connects ground over its No. 1 contact, an operating circuit is established over the back contact of relay AA, through the lower winding of relay A and condenser C3 connected in parallel therewith, through resistance R5 to battery. Relay A does not immediately operate in this circuit, but condenser C3 becomes charged and when the charging current through the condenser decays, relay A then operates, closes a charging circuit for condenser C4 over its No. 2 front contact and through resistance R6 to battery, closes a circuit from ground over its No. 4 contact, thence in parallel through the winding of relay AA and condenser C5 to battery through resistance R1 and at its No. 3 contact prepares the operating circuit of relay B. Condenser C5 now charges and as soon as the charging current flowing therethrough decays sufficiently, relay AA operates and opens the operating circuit of relay A, but relay A does not immediately release since it is maintained operated by the discharge current from condenser C3 through its winding. As soon as the discharge current from condenser C3 decays sufficiently, relay A releases and opens the operating circuit of relay AA. Relay AA does not release immediately, however, since it is maintained operated until the discharge current from condenser C5 through its winding decays sufficiently. As soon as relay AA releases, the operating circuit for relay A and the charging circuit for condenser C3 are reestablished and relay A reoperates in turn causing the reoperation of relay AA. Relays A and AA are thus timed in their operation and release by condensers C3 and C5 and continue to operate and release periodically.

As soon as the first digit keyed by the operator has been registered in the first register RG1 and sequence relay X has operated as previously described, at which time sequence relay Y has not yet operated, a circuit is established from ground over the No. 5 back contact of relay Y, the No. 5 front contact of relay X, conductor FZL to battery through the operating winding of relay FZ which operates and is instrumental in extinguishing the supervisory lamp at the operator's position. As soon as the second digit keyed has been registered and sequence relay Y has operated, as previously described, ground is disconnected from conductor FZL at the No. 5 back contact of sequence relay Y and relay FZ thereupon releases and connects ground to the sender start conductor STL from ground at the No. 6 front contact of relay S, over the No. 3 back contact of relay NU, No. 1 back contact of relay FZ, No. 2 back contact of relay PC and the No. 4 back contact of relay PA. When the third digit has been keyed and registered and consequently sequence relay Z has operated, this starting ground is extended over the No. 2 contact of relay Z and the No. 3 contact of the impulse generating relay A, as soon as relay A operates as previously described, through the winding of relay B to battery.

Relay B upon operating, locks over its No. 4 contact and the No. 2 contact of relay Z to ground on conductor STL independently of the operated or unoperated condition of relay A and,

at its No. 5 contact establishes an obvious operating circuit for relay PP which then operates and at its No. 3 front contact establishes the charging circuit for condenser C2.

Upon the first release of impulse generating relay A, with relay B operated, the out-pulsing circuit for setting the first group selector is established which may be traced from ground over the No. 1 contact of relay B, the No. 1 back contact of relay A, conductor IL, the No. 1 back contact of relay PB to the control circuit of the first group selector. At the same time a circuit is established from ground through condenser C4, the No. 2 back contact of relay A, the No. 3 front contact of relay B, the No. 4 back contact of counting relay E, the No. 3 back contact of counting relay D and through the No. 3 back contact and lower winding of counting relay C to ground. Condenser C4 discharges over this circuit thereby causing the operation of relay C which then locks in a circuit from battery through its upper winding and No. 2 contact, the No. 1 back contact of relay D, the lower back contact of polarized relay P, to ground over the No. 2 contact of relay B. Upon the next operation of relay A the out-pulsing circuit is opened and the charging circuit for condenser C4 is again closed.

When relay A next releases the out-pulsing circuit is again closed and a discharge circuit for condenser C4 is closed as previously traced to the No. 3 back contact of counting relay D, thence over the No. 3 front contact of counting relay C to ground through the lower winding of counting relay D. The discharge of condenser C4 over this circuit causes the operation of relay D which then locks in a circuit from battery through its upper winding and No. 2 contact, No. 1 back contact of relay E, lower back contact of relay P to ground at the No. 2 contact of relay B and at its No. 1 back contact opens the locking circuit of relay C which thereupon releases. Upon the next operation of relay A, the out-pulsing circuit is opened and the charging circuit for condenser C4 is again closed.

Two impulses have now been transmitted over the out-pulsing circuit to the group selector and at this time counting relay D is operated, counting relays C and E are unoperated and transfer relay XX is unoperated. It having been assumed that condenser Cb1 of the first register RG1 has been charged negatively to register the first keyed digit 2, a discharge circuit for condenser Cb1 is now established. This circuit may be traced from ground, through this condenser, the No. 3 back contact of relay XX, the No. 6 back contact of counting relay E, the No. 4 contact of counting relay D, the No. 5 back contact of counting relay C, thence in parallel to the oppositely poled rectifiers Rp and Rq, the rectifier Rq being so poled as to offer a low resistance to the discharge current from the negatively charged condenser Cb1 and the rectifier Rp being poled to offer a high resistance. The effective discharge circuit for condenser Cb1 therefore extends through the lower winding of relay Q and the No. 1 front contact of relay A to ground over the No. 1 contact of relay B and the discharge current from condenser Cb1 therefore operates relay Q which thereupon locks in a circuit extending from ground over the No. 1 contact of relay B, the No. 1 front contact and upper winding of relay A, the locking contact and upper winding of relay Q, the No. 1 back contact of sequence relay Y, the No. 1 back contact of se-

quence relay X, conductor PAL, the No. 5 back contact of relay PB, the No. 3 back contact of relay PR to battery through the winding of relay PA. Relay A is held operated over this circuit to arrest the transmission of further impulses and relay PA is operated.

Relay PA upon operating locks in a circuit from battery through its winding and No. 3 contact, the No. 2 back contact of relay PC, the No. 1 back contact of relay FZ, the No. 3 back contact of relay NU to ground at the No. 6 contact of relay S and at its No. 4 contact removes ground from conductor STL thereby releasing relay B. When relay B releases it opens at its No. 1 contact the locking circuits of relays A and Q, opens at its No. 2 contact the locking circuit of counting relay D and at its No. 5 contact opens the operating circuit of relay PP. Relays A, Q, D and PP now release.

Relay PP upon releasing closes a discharge circuit for condenser C2 which may be traced from ground therethrough, over the No. 3 back contact of relay PP, No. 8 back contact of relay CA, thence through the No. 3 back contact and upper winding of sequence relay X to ground. Relay X now operates by the discharge current from condenser C2, locks in a circuit from battery through its lower winding and No. 4 contact and over the lower contact of relay ZZ to ground on conductor GD and closes an obvious circuit for transfer relay XX which now functions to disconnect the condensers of the first register RG1 from conductors extending to contacts of the counting relays and to connect the condensers of the second register RG2 with such conductors.

The group selector now trunk hunts in the usual manner and when an idle final selector has been found, relay PR is operated in the manner disclosed in the British patent hereinbefore referred to and locks in a circuit extending from battery, through its winding and No. 2 contact, the No. 2 back contact of relay PB to ground at the No. 1 contact of relay PA. With relay PR operated, ground is reconnected to conductor STL over the No. 6 contact of relay S, the No. 3 back contact of relay NU, the No. 1 back contact of relay FZ, the No. 2 contact of relay PC, the No. 6 front contact of relay PR and the No. 6 back contact of relay PB and when relay A again operates this ground is extended as previously described to the winding of relay B and relay B operates, locks and causes the reoperation of relay PP which again closes the charging circuit of condenser C2.

On the next release of relay A following the reoperation of relay B, the out-pulsing circuit is again closed, but at this time through the control circuit of the final selector and the discharge circuit for condenser C4 previously traced is extended through the lower winding of counting relay C and relay C operates and locks as before described. On the next operation of relay A, condenser C4 is recharged and the out-pulsing circuit is opened. When relay A again releases the out-pulsing circuit is again closed and the discharge circuit for condenser C4 is extended, as previously described, through the lower winding of counting relay D which thereupon operates, locks and causes the release of relay C.

With counting relay D operated, counting relays C and E unoperated, transfer relay XX operated and condenser Cb2 of the second register RG2 positively charged to register the second digit 7, a discharge circuit is now established from

ground, through condenser Cb2, the No. 3 back contact of transfer relay YY, the No. 3 front contact of transfer relay XX, the No. 6 contact of counting relay E, the No. 4 contact of counting relay D, the No. 5 back contact of counting relay C, through rectifier Rp and the lower winding of relay P to ground. Relay P is now operated by the discharge current from condenser Cb2, but since rectifier Rq offers a high resistance, relay Q does not operate. Relay P upon operating locks in a circuit from battery through its upper winding and upper contact, No. 3 normal contacts of relay R to ground at the No. 2 contact of relay B, opens at its lower back contact the locking circuit of counting relay D, which thereupon releases, and establishes a circuit from ground at the No. 2 contact of relay B over the lower front contact of relay P, the No. 1 back contact of counting relay C to battery through the winding of relay R. Relay R operates and locks over its Nos. 1 and 3 front contacts to ground at the No. 2 contact of relay B and at its No. 3 contacts opens the locking circuit of relay P which now releases.

When relay A again operates, the out-pulsing circuit is again opened and condenser C4 is recharged. On the next release of relay A the out-pulsing circuit is closed and a discharge circuit for condenser C4 is established as previously traced through the lower winding of counting relay C and relay C operates and locks. In response to the next operation and release of relay A the out-pulsing circuit is again opened and then closed and condenser C4 is charged and with counting relay C operated, is discharged through the lower winding of counting relay D. Relay D thereupon operates, locks and causes the release of counting relay C as previously described.

On the next operation of relay A the out-pulsing circuit is opened and condenser C4 is recharged. When relay A again releases, the out-pulsing circuit is closed and a discharge circuit for condenser C4 is established as previously traced over the No. 4 back contact of counting relay E, thence over the No. 3 front contact of counting relay D to ground through the lower winding of counting relay E and relay E operates, locks in a circuit from battery through its upper winding and No. 3 contact, over the lower back contact of relay P to ground at the No. 2 contact of relay B and at its No. 1 back contact opens the locking circuit of relay D which now releases.

When relay A again operates, the out-pulsing circuit is opened and condenser C4 is recharged and when relay A again releases, the out-pulsing circuit is closed and a discharge circuit for condenser C4 is established as previously traced over the No. 3 contact of relay B, the No. 4 front contact of counting relay E and through the No. 3 back contact and lower winding of counting relay C to ground. Relay C now operates and locks in a circuit from battery through its upper winding and No. 2 contact, the No. 1 front contact of counting relay E, the lower back contact of relay P to ground at the No. 2 contact of relay B. On the next operation of relay A, the out-pulsing circuit is again opened and condenser C4 is recharged.

When relay A again releases, the out-pulsing circuit is closed and a discharge circuit for condenser C4 is established as previously traced over the No. 4 front contact of counting relay E, the No. 3 front contact of counting relay C to ground through the lower winding of counting relay D

and relay D operates, locks from battery through its upper winding and No. 2 contact, over the No. 4 front contact of relay C, the No. 2 front contact of relay E, the lower back contact of relay P to ground at the No. 2 contact of relay B. Relay A again operates, opens the out-pulsing circuit and closes the charging circuit for condenser C4.

Relay A has now transmitted seven impulses for setting the final selector and when it next operates with counting relays C, D and E all operated and relay R operated, a circuit is established from battery through resistance R8, No. 2 front contact of relay R, No. 7 contact of relay C, No. 6 front contact of relay D, No. 5 contact of relay E, through rectifier Rq and the lower winding of relay Q, the No. 1 front contact of relay A to ground at the No. 1 contact of relay B. Relay Q operates and locks in a circuit from ground over the No. 1 contact of relay B, the No. 1 front contact and upper winding of relay A, the contact and upper winding of relay Q, the No. 1 back contact of sequence relay Y, the No. 1 front contact of sequence relay X, conductor PBL, the No. 4 contact of relay PR, through the winding of relay PB to battery.

Relay A is held operated over this circuit to arrest the transmission of further impulses and relay PB operates, locks in a circuit extending from battery through its winding and No. 3 contact, the No. 8 contact of relay PA, the No. 1 contact of relay FZ and thence as traced to ground at the No. 6 contact of relay S and at its No. 6 back contact disconnects ground from conductor STL thereby releasing relay B which in turn releases relays A, Q, C, D, E, R and PP.

Relay PP upon releasing closes a discharge circuit for condenser C2 which may be traced from ground therethrough, over the No. 3 back contact of relay PP, the No. 8 back contact of relay PA, the No. 3 front contact of sequence relay X, thence through the No. 4 back contact and upper winding of sequence relay Y to ground. Relay Y now operates by the discharge current from condenser C2, locks in a circuit from battery through its lower winding and No. 3 contact and over the lower contacts of relay ZZ to ground on conductor GD and closes an obvious circuit for transfer relay YY which functions to disconnect the condensers of the second register RG2 from conductors extending to the contacts of the counting relays and to connect the condensers of the third register RG3 with such conductors.

Relay PB upon operating also opens the locking circuit of relay PR which then releases and reconnects ground from the No. 6 contact of relay S as traced over the No. 2 contact of relay PC, the No. 6 back contact of relay PR, the No. 6 front contact of relay PB, to conductor STL and when relay A again operates, relay B operates, locks and causes the reoperation of relay PP. Relay PP upon operating again closes the charging circuit of condenser C2.

On the next release of relay A following the reoperation of relay B, the out-pulsing circuit is again closed for controlling the rotary movement of the final selector and the discharge circuit for condenser C4 previously traced is extended to the lower winding of counting relay C and relay C operates and locks as before described. On the next operation of relay A, the out-pulsing circuit is opened and the charging circuit for condenser C4 is closed. When relay A again releases the out-pulsing circuit is again closed and the discharge circuit for condenser C4 is extended

as previously traced through the lower winding of counting relay D which thereupon operates, locks and causes the release of relay C. When relay A again operates, the out-pulsing circuit is opened and the charging circuit for condenser C4 is closed.

On the next release of relay A the out-pulsing circuit is closed and the discharge circuit of condenser C4 is established as previously traced over the No. 4 back contact of counting relay E, the No. 3 front contact of counting relay D and thence through the lower winding of counting relay E to ground and relay E operates, locks in a circuit from battery through its upper winding and No. 3 contact, the lower back contact of relay P to ground over the No. 2 contact of relay B and at its No. 1 back contact opens the locking circuit of relay D which thereupon releases. When relay A again operates, the out-pulsing circuit is opened and the charging circuit for condenser C4 is closed.

On the next release of relay A the out-pulsing circuit is closed and the discharge circuit of condenser C4 is established as previously traced over the No. 3 contact of relay B, the No. 4 front contact of counting relay E, through the No. 3 back contact and lower winding of counting relay C to ground and relay C operates and locks in a circuit from battery through its upper winding and No. 2 contact, the No. 1 front contact of relay E thence as traced to ground at the No. 2 contact of relay B. When relay A again operates the out-pulsing circuit is opened and the charging circuit from condenser C4 is closed.

On the next release of relay A the out-pulsing circuit is closed and the discharge circuit for condenser C4 is established as previously traced over the No. 4 front contact of counting relay E, the No. 3 front contact of counting relay C, through the lower winding of counting relay D to ground and relay D operates and locks in a circuit from battery through its upper winding and No. 2 contact, the No. 4 contact of relay C, the No. 3 contact of relay E thence to ground at the No. 2 contact of relay B. Relay A again operates to open the out-pulsing circuit and to close the charging circuit for condenser C4.

Relay A has now transmitted five impulses in the third digit series and upon operating with counting relays C, D and E all operated and relay R unoperated, a discharge circuit is established from condenser Ce3 of the third register RG3 which was assumed to be charged negatively to register the keyed digit 5. This circuit may be traced from ground through this condenser over the No. 6 front contact of transfer relay YY, the No. 6 front contact of transfer relay XX, the No. 2 back contact of relay R, the No. 7 contact of counting relay C, the No. 6 front contact of counting relay D, the No. 5 contact of counting relay E through rectifier Rq, lower winding of relay Q, No. 1 front contact of relay A to ground at the No. 1 contact of relay B. Relay Q operates and locks in a circuit from ground at the No. 1 contact of relay B, through the No. 1 front contact and upper winding of relay A, the contact and upper winding of relay Q, the No. 1 front contact of sequence relay Y, conductor PCL, the No. 4 contact of relay PB, the No. 5 contact of relay PR, through the winding of relay PC to battery.

Relay A is held operated over this circuit to arrest the transmission of further impulses and relay PC operates, locks over its No. 1 contact to the locking circuit previously traced for relay PB and opens at its No. 2 contact the locking circuit

of relay PA. Relay PA thereupon releases opening at its No. 8 contact the locking circuits of relays PB and PC which thereupon release. When relay PC operated it removed ground at its No. 2 contact from conductor STL thereby releasing relay B which in turn releases relays A, Q, C, D, E and PP. Relay PC upon operating also at its No. 3 contact disconnects ground from conductor GD thus restoring all other operated relays of the sender.

While the control of registration for only the three digits 2, 7 and 5 has been described it is believed that it will be obvious how the remaining digits may be registered, it being borne in mind that the a, b, c, d and e condensers of any register are charged negatively by the depression of digit keys 1, 2, 3, 4 and 5, respectively, and that these condensers are charged positively by the depression of digit keys 6, 7, 8, 9 and 0, respectively. On out-pulsing for digits 1, 3 and 4 registered by a negatively charged a, c or d condenser of any register, out-pulsing is stopped by the operation of relay Q after one, three or four impulses have been transmitted, counting relay C being operated alone to establish the circuit of relay Q through a negatively charged condenser a after one impulse has been transmitted, counting relay E being operated alone to establish the circuit of relay Q through a negatively charged condenser c after three impulses have been transmitted and relays C and E being both operated to establish the circuit of relay Q through a negatively charged condenser d after four impulses have been transmitted.

On out-pulsing for digits 6, 8, 9 and 0 registered by a positively charged a, c, d or e condenser of any register, relay P is operated after one, three, four or five impulses have been transmitted and causes the operation and locking of relay R as an indication that five additional impulses should be sent, relay P being operated by the discharge of a condenser a with only counting relay C operated, relay P being operated by the discharge of a condenser c with only relay E operated, relay P being operated by the discharge of a condenser d when both counting relays C and E are operated and relay P being operated by the discharge of condenser e with all of the counting relays C, D and E operated. When relay P operates, the operated counting relays are released but pulsing is not arrested, the transmission of five additional impulses being arrested by the operation of relay Q only after the counting relays C, D and E have been reoperated and remain operated.

Should the operator make an error in keying up a line designation or for any other reason should desire to cancel the number registered, she may operate the release key RK thereby closing a circuit over conductor CAL through the winding of relay CA to battery. If transfer relay XX is not at the time operated, relay CA upon operating will establish circuits from ground over its Nos. 2 to 6 contacts and over back contacts of relay XX to ground through the condensers of the first register group RG1 whereby any charged condenser in the group will be discharged and, will also establish an operating circuit for sequence relay X which may be traced from battery through resistance R1, No. 6 contact of relay Z, the No. 8 front contact of relay CA, the No. 3 back contact and upper winding of sequence relay X to ground. Relay X will thereupon operate, lock in a circuit from battery through its lower winding and No. 4 contact, the

No. 3 contact of relay Z to ground at the No. 7 contact of relay CA and will establish the operating circuit of transfer relay XX.

With relays CA and XX operated a discharge circuit for any charged condenser of group RG2 is established over a lower contact of relay CA, a front contact of relay XX and a back contact of transfer relay YY. A circuit is also established from battery through resistance R1, the No. 6 contact of relay Z, the No. 8 front contact of relay CA, the No. 3 front contact of relay X, thence through the No. 4 back contact and upper winding of sequence relay Y to ground whereupon relay Y operates, locks to the locking circuit of relay X and causes the operation of transfer relay YY. With relays CA and YY operated, a discharge circuit for any charged condenser of group RG3 is established over a lower contact of relay CA and front contacts of relays XX and YY.

As soon as relay Y operates an operating circuit for relay Z is established from battery, through resistance R1, thence as traced over the No. 3 front contact of relay X, the No. 4 front contact of relay Y to ground through the upper winding of relay Z and relay Z operates, locks under the control of relay CA, causes the operation of relay ZZ and opens the locking circuits of relays X and Y which thereupon release in turn releasing relays XX and YY.

If the transmission of impulses is taking place at the time relay CA operates, ground connected to conductor FZL over the No. 1 contact of relay CA causes the operation of relay FZ to remove ground from start conductor STL to release relay B and thereby arrest the transmission of further impulses.

Relay CA is shunted by a non-inductive resistance which makes it sufficiently slow to release to insure a complete cancellation of the registered line number even if the release key RK is only momentarily operated.

What is claimed is:

1. In a signaling system, a digit recording device, a plurality of groups of condensers, means controlled by said recording device for selectively placing condensers of successive groups in a positively or negatively charged condition to register successively recorded digits, any selected condenser of each group being positively charged to register a certain digit value or negatively charged to register a different digit value, impulse transmitting means and means controlled by the charged condensers for causing said impulse transmitting means to successively transmit series of impulses, the number of impulses in each series depending on the particular condenser of a group having a charge thereon and upon the polarity of said charge.

2. In a signaling system, a keyset, a plurality of groups of condensers, means controlled by the successive operation of keys of said keyset for selecting successive groups of said condensers, further means controlled by operated keys of said keyset for placing a condenser of each selected group in a positively or negatively charged condition to register the digits keyed, any selected condenser of each group being positively charged to register a certain digit value or negatively charged to register a different digit value, impulse transmitting means and means controlled by the charged condensers for causing said impulse transmitting medium to successively transmit series of impulses, the number of im-

pulses in each series depending upon the particular condenser of a group having a charge thereon and upon the polarity of said charge.

3. In a signaling system, a digit recording device, a group of condensers for storing digits, means controlled by said recording device for charging any one of said condensers negatively to store certain digits, a condenser of larger capacity than said storing condensers, means for charging said latter condenser, and means controlled by said recording device for discharging said latter condenser into any one of said storing condensers to charge said storing condenser positively to store certain other digits.

4. In a signaling system, a digit recording device, a group of five condensers for storing digits, means controlled by said digit recording device for charging any one of said condensers negatively to store digits 1 to 5, inclusive, or positively to store digits 6 to 0, inclusive, impulse transmitting means, impulse counting means, two oppositely polarized relays associable with successive ones of said condensers by said impulse counting means, one of said relays being operable by the discharge of a positively charged condenser when five less impulses than the numerical value of the digit stored have been transmitted, and means controlled by said one relay and said impulse counting means for operating said other relay to terminate the operation of said impulse transmitting means when five additional impulses have been transmitted, said other relay being operable by the discharge of a negatively charged condenser when impulses corresponding in number to the numerical value of the digit stored have been transmitted to terminate the operation of said impulse transmitting means.

5. In a signaling system, a digit recording device, a digit register controlled thereby, an impulse generating device for transmitting impulses, a train of counting relays less in number than the maximum number of any series to be transmitted, means controlled by said impulse generating device for successively operating said counting relays in rotation, means operative if the digit registered is more than five when five less impulses than the required number have been transmitted for releasing said counting relays, means thereafter effective for again rendering said counting relays successively operable under the control of said impulse generating device to count five additional impulses, and means controlled by said counting relays for terminating the transmission of impulses when the total number transmitted corresponds to the numerical value of the digit registered.

6. In a signaling system, a digit recording device, a plurality of registers for storing digits, means controlled by said recording device for selectively operating said registers to store successively recorded digits, an impulse transmitting means, an impulse counting means, a train of sequence relays for controlling the successive association of said registers with said recording

device and for thereafter controlling the successive association of said registers with said impulse counting means whereby said impulse transmitting means is controlled to transmit series of impulses in accordance with the digits stored in said registers, and means controlled first by said recording device and later by said impulse transmitting means for successively operating said sequence relays comprising a control relay, a condenser, a charging circuit for said condenser completed upon each operation of said control relay, and a discharge circuit for said condenser completed successively through the windings of said sequence relays upon successive releases of said control relay.

7. In a signaling system, a digit recording device, a plurality of registers for storing digits, means controlled by said recording device for selectively setting said registers to store successively recorded digits, an impulse transmitting means, an impulse counting means, a train of sequence relays, means controlled by said recording device for successively operating and locking said relays during the storing of digits to successively associate said registers with said recording device, means to release said relays following the setting of said registers, and means controlled by said impulse transmitting means for reoperating said control means for successively reoperating said relays during the transmission of impulse series to successively associate said registers with said impulse counting means.

8. In a signaling system, a digit recording device, a plurality of registers for storing digits, means controlled by said recording device for selectively setting said registers to store successively recorded digits, an impulse transmitting means, an impulse counting means, a train of sequence relays, means controlled by said recording device for successively operating and locking said relays during the storing of digits to successively associate said registers with said recording device, means to release said sequence relays following the setting of said registers, and means controlled by said impulse transmitting means for reoperating said control means for successively reoperating said sequence relays during the transmission of impulse series to successively associate said registers with said impulse counting means, said control means comprising a relay, a condenser, a charging circuit for said condenser completed upon each operation of said relay in response either to the recording of a digit in said recording device or to the transmission of series of impulses, and a discharge circuit for said condenser completed successively through the windings of said sequence relays upon successive releases of said control relay in response either to the completion of the recording of each digit or to the completion of the transmission of each series of impulses.
